UNITED STATES PATENT OFFICE.

HENRY WARMICK AND ANNETTA WARMICK, OF GRAND RAPIDS, MICHIGAN, ASSIGNEES
OF ONE-THIRD TO JOSEPH FORD AND STANLEY BARNETT, BOTH OF GRAND RAPIDS,
MICHIGAN.

APPARATUS FOR TRANSMITTING AND RECORDING MESSAGES.

1,314,721.

Specification of Letters Patent.

Patented Sept. 2, 1919.

Application filed November 1, 1918. Serial No. 260,700.

To all whom it may concern:

Be it known that we, HENRY WARMICK and ANNETTA WARMICK, both citizens of the United States, and residents of Grand Rapids, in the county of Kent and State of Michigan, have invented certain new and useful Improvements in Apparatus for Transmitting and Recording Messages; and we do hereby declare that the following is

10 a full, clear, and exact description thereof.

Our invention relates to new and useful improvements in apparatus for transmitting messages through the medium of electrical impulses.

15 It is primarily the object of our invention to provide an apparatus associated with a telephone system for procuring a written record of messages transmitted over said system, whereby during the absence of a

20 subscriber from one of the sub-stations of the system, messages from other sub-stations may be permanently recorded at said sub-station for the edification of a person or persons having authorized access to the

25 sub-station.

It is more particularly our object to provide an apparatus of this character operable in conjunction with conventional typewriter mechanisms for printing the messages.

30 It is further our object to provide a sub-station printing mechanism operable for either sending or receiving actuating impulses over the line wires of the telephone system.

35 With the above and other objects and advantages, in view, which will be apparent as the description proceeds, our invention resides in the novel features of construction, combination and arrangement of parts 40 as hereinafter described and defined by the appended claims.

In the accompanying drawings:

Figure 1 is a diagrammatic view of our improved apparatus.

45 Fig. 2 is a diagrammatic view of the printing telegraph mechanisms.

Fig. 3 is a sectional view through the printing mechanism on a plane indicated by the line 3-3 of Fig. 2.

50 Referring now more particularly to the accompanying drawings, B and C desig-

nates each of a pair of subscribers' stations connected with the central station by pairs of line wires 10 in which are disposed plugs 11 at a central station A whereby the subscribers' stations may be placed in circuit with each other or with other stations in the system, in the usual manner, a suitable source of energy such as the batteries 12 being disposed in the line circuit as shown 60 in Fig. 2. Each of the subscribers' stations includes a telephone set D and a cabinet inclosed printing mechanism E disposed in parallel in the line circuit and thus operating impulses may be transmitted over the circuit either from one telephone set to the other, or from one printing mechanism to the other, in accordance with the nature of the message and the conditions involved. The printing mechanisms are identical in 70 nature and hence but a single mechanism 65 will be specifically described.

Each of the printing mechanisms preferably embodies a conventional typewriter structure and is adapted to print letters and figures. While each typewriter mechanism will include a sufficient complement of character elements, for the sake of clarity I have shown but four character elements 20 carried by type-levers 21 mounted on a pivot 80 bar 22 and adapted to impinge against paper trained about a conventional platen 23. For actuating the type levers, a plurality of key bars 24 are mounted on a shaft 25 extending under the type bars, and are provided thereadjacent with upstanding fingers 26 engageable with lateral pins 27 on the lower ends of the type levers. The remote ends of the key bars are provided with upstanding key posts 28 which are manually 90 engageable to rock the bars and impart printing impulses to the type levers 21. Although not shown, certain of the key bars 24 may also actuate conventional line spacing and gear shift mechanisms so as to procure the necessary movements of the platen in transmitting a message of considerable length.

Mounted over the set of type bars, which are resiliently urged to initial position by springs 29, is a shaft 30 which has clutch connection 31 with a conventionally shown

spring motor 32 adapted to procure continuous rotation of the shaft at a fairly high speed, this clutch being controlled by a lever 32 carrying the armature of a magnet 33 whereby the clutch may be shifted as will be later described.

This shaft carries a series of disks 34 corresponding in number to the number of key bars 24 and each disposed over a corresponding key bar and provided with a radial projection 35 engageable against an upstanding abutment 36 on the key bar. A pin 37 extends laterally from each radial projection and said projections are mutually spaced circumferentially of the disks whereby upon movement of the shaft and disks toward the key bar, only one of said radial projections may engage its key bar abutment. The shaft 30 is mounted on a swinging frame including journal arms 38 pivoted on a stationary shaft 39 and the frame is normally held in raised position by a retractile spring 40 secured to one of said arms and to a suitable support above the arm, upward movement of the frame being limited by a stationary abutment member 41.

We provide an escapement action for the rotary actuator formed by the shaft and disks, whereby upon escapement movement of the shaft corresponding electrical impulses will be transmitted over the line circuit to control the rotary actuator of another printing mechanism. Thus, an escapement lever 42 is pivoted at 43 above the rotary actuator and has its lower end bifurcated to embrace a ratchet wheel 44 mounted on the shaft 30 and having a number of teeth corresponding to the number of key bars. One of the furcations of this lever is adapted to abut the teeth and the other furcation has its free end inwardly directed to engage the teeth whereby upon rocking movement of the lever the shaft is permitted intermittent rotative impulses under the influence of the spring motor 32. The lever is resiliently urged to rocking movement in one direction by a spring 45, and it is moved against the action of this spring by a magnet 46 having its armature 47 secured to the lever. One of the line wires 10 is connected with the magnet 46, and the other line wire is connected with a spring finger 48 which co-acts with a stationary finger 49 connected by a wire 50 with the magnet 46. The spring finger 48 is normally urged by its resiliency away from the finger 49, and it is moved into engagement with the stationary finger by contact successively with circumferential projections 51 on a wheel 52 mounted on the shaft 30, the projections 51 corresponding in number to the number of key bars.

Thus an electrically operated escapement action is provided, and the escapement impulses are transmitted over the line wire

whereby the escapement movements of the rotary actuator of another subscriber station may be synchronized therewith. A switch 53 is provided for short circuiting the contacts 48 and 49 whereby to render the escapement mechanism inactive with respect to the transmission of impulses over the line circuit.

A shaft 54 extends transversely of the bank of key bars 24, and pivotally mounted on this shaft are a series of angular levers 55 each having one arm in pin and slot connection with a corresponding key bar. Mounted on the other arm of each lever is a spring contact finger 56 engageable with the lateral pin 37 of the corresponding disk 34 and adapted to be urged by such engagement against a stationary contact finger 57 carried by the arm, this engagement occurring upon depressing action of one of the key bars, whereby to close a circuit through said contacts and whereby at the same time to stop the rotary actuator with the corresponding radial projection 35 over the abutment 36 of the actuated key bar. One of the contacts of the lever 55 is connected by a wire 58 with one of the line wires, while its other contact is connected by a wire 59 with a set of batteries 60 which are in turn connected with a switch 61 from which wires 62 and 63 extend respectively to an actuating depressing magnet 64 and to one of the line wires. This magnet 64 is also connected by a line wire 64^a with the other line wire 10, and is adapted to attract an armature 65 carried by the rocking frame of the rotary actuator. Wires 66 and 67 of the telephone set D are connected with the line wires 10 in advance of the various magnet and switch connections, and thus upon opening both the switches 53 and 61, a conventional telephone circuit system is procured.

Each printing mechanism is adapted to either send or receive messages. Taking up now the correlative operation of the printing mechanisms, and assuming that the mechanism of the subscriber's station is sending and the mechanism of the station C is receiving, it is noted that to adapt a station for sending, the switch 53 is opened and the switch 61 is closed, while to adapt a station for receiving, the switch 53 is closed and the switch 61 is opened. As soon as the central operator closes the circuit connecting the two stations, the escapement mechanism of the station B will become active, to procure rapid intermittent rotative steps of the rotary actuator of said station and to transmit impulses over the line wire procuring a corresponding and synchronized escapement rotation of the actuator of the station C, it being noted that this rotation of the actuator of the station C does not set up impulses in the circuit by

reason of closing the switch 53 across the contacts of the escapement. Tracing the circuit in this actuation, it is noted that current passes from one of the line wires 10 through the magnet 46, the wire 50, and the intermittently engaged contacts 48 and 49 of one station to the other line wire 10, and from thence through the switch 53 of the receiving station and the wire 50 and magnet 46 to the other line wire. A circuit is also open through the magnet 64, but the current supplied through the line circuit is not of sufficient strength to attract the armature 65 of the swinging frame. By this operation, the corresponding radial projections 35 of the rotary actuators of the two stations are simultaneously placed in opposition to their type bars 24.

When the operator depresses one of the key bars 24, the contact arm of the lever 55 will be swung into the path of the corresponding pin 37, to stop said pin and projection 35 over the type bar abutment 36, and at the same time to stop a projection 35 of the actuator of the other station in opposition to the corresponding type bar, by reason of halting the escapement operation. At the same time, the contacts 56 and 57 will be brought together and increased current will be thrown in the circuit of the magnets 64 of the two stations, to procure sufficient energization of said magnets to depress the rotary actuators by rocking the swinging frames thereof. This depressing movement of the actuator of the receiving station C actuates the selected type bar to impart a printing stroke to the type lever 21. The actuator of the sending station B merely moves idly downward.

An exceedingly simple printing telegraph mechanism has thus been provided in conjunction with a telegraph system, whereby either verbal or printed communications may be transmitted so that, should it not be possible for a person to answer the phone, or should the nature of the message transmitted be secret, the message may be printed out, being thus unintelligible to a party listening in on a line circuit.

To insure correspondence of the relative positions of the printing mechanisms of the various stations, each operator at the termination of a printed message depresses a previously agreed upon key, which is the same in each instance and may constitute any one of the ordinary keys of the mechanism, halting the actuator in a common rest position for all the mechanisms and then closes the switch 53 whereby subsequent relations of the escapement mechanism will be in correspondence with the escapement mechanism of another station.

The magnet 33 of each printing mechanism, which controls the motor clutch 31, is bridged across the line wires, and thus upon

completion of a line circuit between a pair of printing mechanisms, the clutches of both mechanisms will be actuated to procure driving impulses of the rotary actuators shafts.

70

What is claimed is:

1. An apparatus of the class described including a pair of printing mechanisms, each mechanism including a series of movable type actuating bars, shiftable rotary actuators mounted adjacent the series of bars and provided with radial projections each adapted to move a corresponding bar, means for procuring synchronized intermittent rotative movements of the actuators, and means operable upon moving a printing bar of one mechanism for shifting the actuator of the other mechanism to engage its radial projection with and move a corresponding bar of the other printing mechanism.

85

2. An apparatus of the class described including a pair of printing mechanisms, each mechanism including a series of movable type actuating bars, shiftable rotary actuators mounted adjacent the series of bars and provided with radial projections each adapted to move a corresponding bar, an escapement mechanism associated with each rotary actuator and including an operating magnet, a circuit connecting the magnets, means in said circuit operable selectively by each escapement mechanism for transmitting escapement impulses over the circuit to the other escapement mechanism, and means operable upon moving a printing bar of one printing mechanism for shifting the actuator of the other printing mechanism to engage its radial projection with and move a corresponding bar of the other printing mechanism.

95

3. An apparatus of the class described including a pair of printing mechanisms, each mechanism including a series of movable type actuating bars, shiftable rotary actuators mounted adjacent the series of bars and provided with radial projections each adapted to move a corresponding bar, means for procuring synchronized intermittent rotative movements of the actuators, magnets controlling shifting movement of the actuators, and means operable upon moving a printing bar of one mechanism for energizing said shifting magnets of both mechanisms.

105

4. An apparatus of the class described including a pair of printing mechanisms, each mechanism including a series of movable type actuating bars, shiftable rotary actuators mounted adjacent the series of bars and provided with radial projections each adapted to move a corresponding bar, means for procuring synchronized intermittent rotative movements of the actuators, magnets controlling shifting movement of the actuators, stop members each movable

110

115

120

125

130

upon movement of a corresponding type actuating bar to engage and stop the rotary actuator of said bars, a switch carried by each stop member and closed upon such engagement, and a circuit including said switches and magnets.

In testimony that we claim the foregoing we have hereunto set our hands at Grand Rapids, in the county of Kent, and State of Michigan.

HENRY WARMICK.
ANNETTA WARMICK.
